Primary Examiner — Karen S Acker(74) *Attorney, Agent, or Firm* — Henry M. Feiereisen LLC;
Ursula B. Day(57) **CLAIM**

The ornamental design for a display screen with graphical user interface for time keeping, as shown and described.

DESCRIPTION

The sole FIGURE is a front view of a display screen with graphical user interface for time keeping showing my new design. The design is shown in blank position.

The dot dash dot line perimeter surrounding the design represents the boundaries of the claim and forms no part thereof.
